UNITED STATES PATENT OFFICE.

CHARLES P. MADSEN, OF NEW YORK, N. Y., ASSIGNOR, BY MESNE ASSIGNMENTS, TO
WILLIAM W. VARNEY, OF BALTIMORE, MARYLAND.

LOUD SPEAKER.

Application filed December 30, 1925. Serial No. 78,492.

This invention relates to telephone apparatus of the type for producing human speech or music of a sufficient degree of loudness to be heard in an ordinary room or in an assembly. It is intended primarily for use in connection with radio apparatus, but it can also be used in connection with ordinary telephone apparatus known as public address systems, and it is also adaptable for use as a means of stepping up the volume or amplifying sound on ordinary phonographs.

There have heretofore been in use two general types of apparatus both depending upon diaphragm action. In one case a very small diaphragm is used and a horn or other means provided for amplifying the sound. In the other case a very large diaphragm is used in the nature of a cone fastened at its edges either with or without a hinge and known to physicists as the tympanum. These apparatuses have serious faults. Both of the diaphragms possess a fundamental note together with harmonies which are not of a musical frequency, the results being that the music or the speech reproduced is highly distorted. In the case of the small diaphragm there is in addition what is known as horn effect; in the case of the large diaphragm very serious mechanical difficulties are encountered. Since the large diaphragm is fastened at its edge to a fixed support and at its apex to the actuating means, any change in the size or shape of the diaphragm due to moisture or temperature affects the actuating means throwing it out of adjustment.

My invention may have the appearance of the large diaphragm type but the similarity is only superficial. It is well known that any body in order to produce or reproduce sound must possess resilience. The reason is that bodies of matter which can be used possess a certain degree of inertia and unless a resilience is opposed to the inertia the sound will be damped. In the case of the large diaphragm telephone reproducers, this resilience is provided by the cone or the hinge in the cone itself. I have discovered that if a resilience is provided at the source of motion sufficient to balance the inertia of the whole system that then no resilience need be provided in the cone nor its fastening and I produce in this manner sounds with any body which is sufficiently light and will maintain its shape.

The object of this invention is to provide

simple and improved means and structures for utilizing the new method of generating air waves of sound frequency disclosed in my co-pending application electrically actuated, said co-pending application being Serial 60 Number 27,206.

This method consists briefly in providing a relatively thin but rigid body of relatively large area with the proper degree of resilience near its support. The body may be of any form which will maintain its shape but I preferably use a cone, in which case it is supported from the apex only and a resilience is provided at the supporting point.

Referring to my pending application, 70 which is provided with a needle for photographic reproduction, in place thereof in this invention I provide an iron armature at the point where the needle usually goes and actuate it by an electro-magnetic system. Any of the several types of the well known electro-magnetic systems may be used, as for instance the single acting system such as is used in ordinary ear phones, or the "push and pull" magnetic system such as is used for 80 alternating current, or the electro-dynamic systems. I have found that my invention enables me to get proportionately greater results over the old art with the ordinary single acting system such as is used in an ordinary 85 telephone receiver. A great fault of that system, when used in the old way with a diaphragm being that when used with direct current such as supplied by an ordinary amplifying tube the diaphragm is pulled from 90 one side only and must return by its own resilience and therefore the reproduction is faulty. A part of my invention consists in providing the necessary resilience without the diaphragm.

A further object of my invention is the providing an improved loud speaker, electrically operated, of extreme sensitiveness.

A further object of my invention is the providing a loud speaker of cheap construction, simple and effective in operation.

A further object of my invention is the providing an improved sound producing device electrically operated by electrical effect, operating on a unit structure sound generating means.

A further object of my invention is the providing in a loud speaker improved means of supporting sound producing device electrically operated.

A further object of my invention is the method of producing air waves of sound frequency by electrical impulses operating on a unit structure producing a torsional effect in the support thereof.

In the drawing of the herein described embodiment of my invention, Fig. 1 is a sectional view in elevation of the preferred embodiment of my invention in which the actuating means is an ordinary bipolar electric unit, such as is now commonly used in ear phones and in many types of loud speakers; Figure 2 is a plan view of the loud speaker shown in Figure 1, with certain parts omitted; Figure 3 is a detailed view of the supporting means between the armature and its support; Figure 4 being a view taken at right angles to the view shown in Figure 3; Figure 5 is a view similar to that shown in Figure 1, in which I have shown a modified means of supporting the armature; Figure 6 being a plan view of the modified reproducer shown in Figure 5 and is a view somewhat similar to Figure 2; Figure 7 is a view in elevation in section of a modified form as adapted to a "push and pull" or "rocker" type of electric unit as may be found in existing loud speaking telephones intended for alternating current; Figure 8 being a reduced view in elevation of that shown in Figure 7; Figure 9 is an enlarged view in elevation in section of the bipolar unit shown in Figure 1 taken at right angles to said view; Figures 10-11-12-13 are enlarged views of details which will be described hereinafter; Figure 14 is an enlarged view in section in elevation taken at right angles to the view shown in Figure 7 of the "pull and push" mechanism; Figures 15-16-17 being enlarged details of said mechanism, and Figure 18 being an inverted plan view of the same.

Similar numerals refer to similar parts throughout the several views.

Referring particularly to Figure 1-1 is the base or supporting plate; 2 and 2' are the permanent or horse-shoe magnets, on which rest soft iron pole pieces 2"-2", around which are the wire bobbins 3 and 3'. Ordinarily the support of the magnets and bobbins are made rigid or integral with the case. I have discovered that it is very much better to keep the same insulated from the case and I do this by placing between these parts and the case a resilient preferably a vulcanized rubber cushion 4, which rests on the bottom of the supporting frame 5; 6 is a screw threaded into supporting frame 5 and bears under washer 7 and is provided with handle.

The object of this arrangement is to provide a means of adjusting very accurately the gap or distance between the pole pieces 2 and 2' and the armature 8 to permit of the use of different voltages. In the preferred form armature 8, which is preferably made of soft Norway iron, is slotted at one end. In this

slot is inserted a piece of clock spring 10, the opposite end of said spring being inserted in a slot in block 9. The distance between armature 8 and block 9 is determined very accurately for correct response by trial. After this distance has been determined, the two parts are adjusted to it and then integrally united by fusing together with pure tin. I preferably do this by applying a mixture of tin dust metal and zinc chloride and then heating to 75 slightly above the melting point of tin, which is below the annealing point of the spring in an electric furnace.

11 is a small metal cone, preferably dur-aluminum, fastened to armature 8, and 12 is the oscillator which is preferably made of bakélite dielecto or vulcanized fibre and may be of a size depending on the power of the electrical unit. With units of such size as are commonly used I find the oscillator, 12, 80 works most efficiently when about 12" in diameter.

Figures 3-9 show in greater detail a modification of the means of supporting armature 8 with the same type of unit. In this modification instead of using a clock spring I provide the armature 8 with a spindle 13, which is surrounded by an organic resilient material, preferably vulcanized rubber, in a high state of tension. This material is initially tensed, as for instance, forcing on a rubber tube whose inside diameter is smaller than that of the spindle, or winding it very tautly with a rubber band. This wound spindle is then compressed between blocks 15 and 16 by means of screws 17. This structure is not so permanent as the preferred form but lends itself to extremely accurate adjustment for correct response.

90 In Figures 13 and 14 is shown a structure of the cone 11 when it is desired to make oscillator 12 removable. This cone 25 is provided with an inside cone 18 and a swivel nut 19.

Figures 10-16 show the embodiment of my invention with what is known as the "push and pull" or "rocker" type of loud speaking telephone intended for alternating current. In this unit 20 and 20' are soft iron pole pieces fastened to the permanent magnet 21. 22 and 22' are the bobbins and 23 is the armature. The action of this type of unit is too well known to need description here. Instead however of supporting this armature in the usual way I support it by means of spindle 24 in blocks 25. Each end of the spindle is provided with a resilient organic material, as rubber, under high tension and compressed by screws 26. Blocks 25 rest upon platform 27, by means of screws 28, which provide a means of centering armature 13 between the pole pieces.

One end of armature 13 is provided with stud 29 upon the upper end of which are cones 11 and 18, between which is clamped 130

the oscillator 12. The size of this oscillator may, in this unit, be much larger than that used in the two other structures. I have found that this type of electrical unit when

5 connected with an adequate electrical supply will operate an oscillator two feet in diameter.

In my improved loud speaker I avoid the error due to moisture absorption by the dia- 10 phragm, also the effect of temperature upon the same and have found that by using a cone whose edge is free and unobstructed the re- sponse is much freer and distortion less and sound more reliable.

Having thus described my invention, what 15 I claim and desire to secure by Letters Patent is—

1. A loud speaker comprising a support in which an armature is fulcrumed or jour- 20 nalled, an armature magnetically operated fulcrumed or journalled in said support, an air vibrator free to vibrate in unconfined space attached to and entirely supported by said armature, and a resilient means connect- 25 ing said support and said armature consist- ing of a fulcrum resiliently supported.

2. In an organized loud speaker provided with an armature, an electric magnet and a supporting case for the same, means of relatively adjusting said armature with refer- 30 ence to the effect of said magnet consisting of an organic resilient member between said magnet and said case and means of varying the tension of said organic resilient member to adjust the magnet.

35 3. In an organized loud speaker provided with an armature, an air vibrator free to vibrate in unconfined space attached to and entirely supported by said armature, an elec- tric magnet and a supporting case for the 40 same, and means of adjusting relatively the

position of said armature and said magnet consisting of adjusting means to adjust said magnet with reference to said supporting case.

4. In an organized loud speaker provided 45 with an armature, an air vibrator attached to and entirely supported by said armature, an electric magnet and a supporting means for the same, and means for adjusting relatively the position of said armature and said 50 magnet consisting of an organic resilient member between said magnet and said sup- porting means and means for varying the tension of said organic resilient member to adjust the magnet. 55

5. In an organized loud speaker provided with a magnet and an armature under the influence of said magnet an air vibrator free to vibrate in unconfined space attached to and entirely supported by said armature, a sup- 60 port for said magnet and said armature relatively positioning the same, adjustable means for tensioning the supporting of said arma- ture to effect the freedom of the vibration thereof while under the influence of said 65 magnet.

6. In an organized loud speaker provided with a magnet and an armature under the influence of said magnet, an air vibrator free to vibrate in unconfined space attached to and entirely supported by said armature, a sup- 70 port for said magnet and said armature relatively positioning the same, adjustable means for tensioning the supporting of said arma- ture to effect the freedom of the vibration thereof while under the influence of said 75 magnet consisting of tightening the holding means of said armature to decrease the free- dom of movement thereof.

CHARLES P. MADSEN.
